UNITED STATES PATENT OFFICE.

VERA MENEFEE, OF LOS ANGELES, CALIFORNIA.

DESIGN FOR A PIN.

Application filed April 2, 1924. Serial No. 9,141. Term of patent 3½ years.

To all whom it may concern:

Be it known that I, VERA MENEFEE, a citizen of the United States, residing at Los Angeles, in the county of Los Angeles and State of California, have invented a new, original, and ornamental Design for a Pin, of which the following is a specification, reference being had to the accompanying drawing, forming part thereof.

The figure is a plan view of a pin.

I claim:

The ornamental design for a pin, as shown.

VERA MENEFEE.
